UNITED STATES PATENT OFFICE.

WILLIAM CAMERON, OF CHICAGO, ILLINOIS, ASSIGNOR TO TORRIS WOLD & COMPANY, OF CHICAGO, ILLINOIS, A CORPORATION OF ILLINOIS.

CLUTCH.

1,261,763.

Specification of Letters Patent. Patented Apr. 9, 1918.

Application filed February 21, 1917. Serial No. 150,005.

To all whom it may concern:

Be it known that I, WILLIAM CAMERON, a citizen of the United States, residing at Chicago, in the county of Cook and State 5 of Illinois, have invented certain new and useful Improvements in Clutches, of which the following is a specification.

This invention relates in general to clutches, but has more particular reference 10 to a clutch which is especially adapted for use on can-making machines and the like, where it is desirable to operate or drive two sets of mechanisms from one source of power.

15 Machines of this type include mechanism for feeding the metal blanks to the body-forming mechanism and also mechanism for conveying the formed bodies through the machine in operative relation to the heating and soldering devices. Whenever it becomes necessary to stop the machine the blank feeding mechanism must, of course, be stopped but if the conveying mechanism were simultaneously stopped the can bodies 20 in the machine which would be subjected to prolonged action of the soldering flames would be ruined.

My present invention, therefore, contemplates the provision of a clutch to which the 25 power is applied and from which it is transmitted to the blank feeding mechanism and to the conveyer mechanism, the clutch being so designed that when the machine is in operation the blank feeding mechanism and 30 the conveying mechanism will be operated in synchronism or predetermined timed relation with respect to each other, and when the clutch is thrown out the blank feeding mechanism will be stopped while the conveying mechanism will continue in operation so 35 as to deliver all of the bodies from the machine and thus prevent them from being burnt or otherwise damaged in the machine.

40 Another object of my invention is to provide a clutch which when the machine is thrown into operation will yield sufficiently to prevent injury to the machine or to the clutch, such as would result from an attempt to instantaneously set in motion at high 45 speed an idle train of mechanisms. My improved clutch, therefore, is designed to slip or yield during initial starting of the machine, or in other words, when the clutch 50 is first thrown in, so that the machine may 55 start slowly and gradually, and as its iner-

tia is overcome the slippage afforded by the clutch will cease so that the power will be transmitted directly without slippage or loss to the machine driven by the clutch.

In order to facilitate an understanding of 60 my invention I have illustrated one preferred embodiment thereof on the accompanying sheet of drawings from which, when considered in connection with the following description, the construction, operation and many of the inherent advantages 65 of my invention should be readily appreciated. Referring to the single figure of the drawing which illustrates a median sectional view through a clutch embodying my invention reference character 1 indicates a shaft upon which the mechanism embodying my invention is mounted, this shaft being the driven shaft by which one set of mechanisms 70 of the machine to which my clutch is applied is operated.

In a can body-forming machine to which my invention is applicable the shaft 1 is connected with and operates the blank feeding mechanism (not shown) of the machine. 80 Upon the shaft there is splined the driven member 2 of a clutch, which is adapted to be shifted longitudinally of the shaft by a suitable forked lever which engages in the groove 3 of a collar formed on the member 2 in the usual manner, rotation of the clutch member with respect to the shaft being prevented by a plurality of splines 4.

The driving member of the clutch, indicated generally by reference character 5, 85 comprises a relatively long bearing sleeve 6 rotatably mounted upon the shaft 1 and held against longitudinal displacement from the shaft by a collar 7 secured to the end of the shaft by a pin 8, or otherwise. In order 90 to afford lubrication between the bearing surfaces of the shaft 1 and the sleeve 6 the shaft is cored out at its outer end to provide an oil or heavy lubricant receptacle 9, from which the lubricant is delivered by a small central bore 11 to one or more transverse openings 12 through which the lubricant is delivered. A cap or plug 13 threaded into the end of the receptacle 9 may be utilized 95 to prevent the escape of the lubricant and also to force the lubricant to the wearing surfaces as the plug is screwed into the receptacle.

Upon the driving member intermediate its ends I have rotatably mounted a power 100

member 14 which, as shown, is in the form of a wheel or pulley to which power is applied by means of a belt in the usual manner from any suitable source of power. The 5 web 15 of the power wheel is thickened a short distance from the center of the wheel, and its faces are ground smooth so as to provide friction surfaces 16 and 17. The driving member 5 is shaped to provide an 10 opposed smooth friction surface 18 adapted to frictionally engage the surface 16.

At the opposite face of the web 15 there is mounted on the hub or sleeve 6 of the driving member a friction ring 19, preferably channel-shaped in cross section, as shown, and having a flat face 21 adapted to frictionally engage the opposed friction surface 17 of the power member. A ring 22 is shaped to enter the channel of the friction 20 ring 19, and both the rings 19 and 22 are splined to the hub or sleeve 6 of the driving member by means of a feather or spline 23. This spline is fixedly secured to the sleeve 6 by screws 24 and the rings 19 and 22 are 25 grooved to slidably fit over and engage the spline.

For the purpose of forcing the ring 19 toward the web 15 so as to cause the friction surfaces 16 and 17 to be engaged by and 30 clamped between the surfaces 18 and 21 the outer end of the sleeve 6 is threaded to receive a ring or collar 25 which may be screwed onto the sleeve until the requisite friction is established between the power 35 member and the driving member. A limited amount of resiliency and flexibility is afforded by a slightly resilient composition ring 26 interposed between the rings 19 and 22, as shown. In order to prevent scoring 40 of the friction surfaces the web 15 is provided with a plurality of transversely disposed bores or apertures 27 which, when the parts are assembled, are filled with graphite or other suitable lubricant, which automatically 45 distributes itself over the frictionally engaged surfaces, thus prolonging the life of the construction.

The driving member 5 is provided with a gear wheel 28 which is secured to its inner 50 face by bolts 29 or otherwise, this wheel being adapted to mesh with and drive a pinion 31 mounted upon a short shaft 32 which is equipped at its other end with a bevel pinion 33 meshing with and driving a companion pinion 34 mounted on a shaft 35 which operates the transferring mechanism 55 previously mentioned. Since the transferring mechanism and the blank feeding mechanism must operate in synchronism or predetermined timed relation when the machine is in operation it is obvious that the driving member 5 must be connected with the shaft 1 in a certain predetermined angular relation thereto. The inner face of the driving member, therefore, is provided with a single en-

gaging or driving shoulder 36 adapted to cooperate with a companion shoulder 37 on the driven member 2 of the clutch, so that when the clutch is thrown in the driving member will always be connected to the shaft 70 1 in a certain predetermined angular position.

The frictional connection between the power member 14 and the driving member 5 is so regulated by adjustment of the ring 75 or sleeve 25 that the driving member will under normal conditions be substantially rigidly connected with the power wheel so as to rotate therewith and continuously drive the shaft 35 which operates the transferring 80 mechanism. When the clutch is thrown out, as shown on the drawings, the power member 14 and the driving member 5 will continue to revolve, thus driving the transferring mechanism while the blank feeding 85 mechanism is permitted to stand idle. When the clutch is again thrown in to start the blank feeding mechanism it will be obvious that because of the positive engagement between the driving and driven members of 90 the clutch an excessive load or strain will be imposed upon the clutch before the inertia of the shaft 1 and the mechanism operated thereby is overcome. Were no provision made for slippage or yieldability between the power wheel 14 and the shaft 1 95 injury either to the clutch or to the mechanism operated by the shaft 1 would result from the effort to instantaneously start the mechanism at high speed. The friction, 100 however, between the power member 14 and the driving member 5 is so regulated that when this excessive strain is imposed upon the driving member by the driven member 2 of the clutch, slippage between the frictional 105 engaging surfaces on the power member 14 and the driving member 5 will occur. This slippage will absorb the shock occasioned by throwing in the clutch and will permit the shaft 1 and the mechanism operated thereby to speed up gradually until the resistance offered to the rotation of the shaft 1 is less than the frictional resistance between the power member and the driving member, whereupon the slippage will cease and the 110 shaft 1 will rotate at the same speed as the power member 14.

It will be manifest from the foregoing that I have provided a clutch which will 115 drive two sets of mechanisms in predetermined synchronism, will continuously drive one mechanism while the other is permitted to remain idle, and will start the idle mechanism in proper timed relation with respect to the continuously operating mechanism 120 without injury to the machine or to the clutch, and will permit this starting mechanism to speed up slowly until it acquires the desired speed, whereupon the yielding or 125 slippage of the clutch will cease and the 130

mechanisms will receive their power directly and without loss from the power member.

While I have illustrated that embodiment of my invention which at the present time seems preferable it should be understood that the invention is capable of embodiment in materially different forms without departing from the essence of the invention as defined in the following claims.

10 I claim:

1. In a clutch, the combination of a shaft, a driving member rotatably mounted thereon, means for connecting said driving member to said shaft in predetermined angular relation, a continuously operating power member, a frictional connection between said power member and said driving member, and mechanism connected with said driving member so as to be operated thereby in synchronization with said shaft.

2. In a clutch, the combination of a driven shaft, a driving member rotatably mounted thereon, clutch mechanism adapted to connect said driving member to said shaft in predetermined angular relation, said driving member being provided with a radially disposed friction face, a friction ring splined on said driving member and having a friction face opposed to said first mentioned friction face, a power member rotatably mounted on said driving member between said faces, and means mounted on the hub of said driving member for adjusting said friction ring so as to frictionally clamp said power member between said friction faces.

3. The combination of a driven shaft, a clutch member splined thereon, a driving member rotatably mounted on said shaft, said driving member including a companion

clutch member and a driving gear, mechanism adapted to be driven from said gear, a power member, and a frictional connection between said power member and said driving member.

4. In a clutch, the combination of a shaft, a driving member rotatably mounted thereon, means for connecting said driving member to said shaft, said driving member having a radially disposed friction face, a continuously operating power member rotatably mounted upon the hub of said driving member, a friction ring splined on said driving member, said power member being disposed between the opposed friction faces of said friction ring and said driving member, a thrust ring in proximity to said friction ring, and a collar threaded onto the hub of said driving member and adapted to be adjusted to force said friction ring into engagement with said power member to produce the requisite degree of friction.

5. In a clutch, the combination of a shaft, a driving member rotatably mounted thereon and provided with a friction face, means for connecting said driving member with said shaft, a friction ring splined on said driving member, a power member disposed between said friction faces and said friction ring, a thrust ring splined on said driving member, a resilient ring interposed between said friction ring and said thrust ring, and an adjustable thrust collar threaded upon said driving member to produce the requisite friction between said power member and the engaging faces of the driving member and the friction ring.

WILLIAM CAMERON.
